(57) **CLAIM**

The ornamental design for a water sampling and monitoring station, as shown and described.

DESCRIPTION

FIG. 1 is a perspective view of a water sampling and monitoring station showing the new design.

FIG. 2 is a front elevational view thereof.

FIG. 3 is a right side elevational view thereof.

FIG. 4 is left side elevational view thereof.

FIG. 5 is rear elevational view thereof.

FIG. 6 is a top plan view thereof.

FIG. 7 is a bottom plan view thereof.

FIG. 8 is a perspective view thereof, showing an open door; and,

FIG. 9 is a perspective view thereof.

The broken line showing is for the purpose of illustrating portions of the article and forms no part of the claimed design.
